UNITED STATES PATENT OFFICE.

EDWARD R. PENROSE, OF LOGANSPORT, INDIANA, ASSIGNOR TO BUDA COMPANY, OF CHICAGO, ILLINOIS, A CORPORATION OF ILLINOIS.

HYDRAULIC JACK.

1,120,968.

Specification of Letters Patent. Patented Dec. 15, 1914.

Application filed January 25, 1913. Serial No. 744,144.

To all whom it may concern:

Be it known that I, EDWARD R. PENROSE, a citizen of the United States, and residing at Logansport, county of Cass, and State of Indiana, have invented certain new and useful Improvements in Hydraulic Jacks, of which the following is a specification, reference being had to the annexed drawings.

My invention relates to the class of hydraulic jacks; and has for its principal object the provision in a jack of novel screening means adapted to screen and protect openings and passages provided in jack parts for the free circulation of the fluid, against the intrusion of foreign matter, and in such relation thereto as to prevent any possibility of such openings becoming clogged, or free valve action hindered by lodgment of extraneous substances in the neighborhood of valve seats.

My invention further purposes to provide an improved jack construction wherein the number of joints and packings is materially reduced; together with a simple and effective arrangement of parts designed to obtain certain and positive operation of the jack.

These, together with such other objects as may hereinafter appear or are incident to my invention, I attain by means of a construction illustrated in preferred form in the accompanying drawings, wherein:—

Figure 1 is a central vertical section through a jack embodying my invention.

Figure 2 is a sectional view of Figure 1 along the line II—II.

Figure 3 is a central vertical section of the integral ram base and valve cylinder.

Figure 4 is a sectional view of Figure 3 on the line IV—IV.

From a practical standpoint, one great disadvantage heretofore has existed which has operated against obtaining the maximum efficiency of a jack of this class, namely:—stoppage or clogging of vital passages by the intrusion and lodgment of foreign matter therein, resulting consequently in the jack being placed more or less temporarily out of service for cleaning or regrinding of parts. This condition is well known particularly in railway and other shops, and is usually evidenced in the operation of the ordinary hydraulic jacks as for example when in pumping with the handle the ram refuses to rise, or again as

still another indication of this condition the operating handle rises when the hand is removed.

The main object of my invention is to overcome this condition, by the application of a novel screening means in such a jack, and suitably located and arranged therein to adequately protect and screen valued passages, or other openings, or co-acting surfaces, against interference by extraneous substances suspended in the liquid, or which may have in any way worked into the jack, and which screening means by reason of its construction and location clears itself of any foreign matter it may have so intercepted.

While I have illustrated my preferred embodiment in the annexed drawings, I do not intend to restrict myself in this connection to the exact details of construction, or to the specific arrangement of parts as shown, as it may be premised, however, that such may be departed from, or the screening means may be applied to other forms or makes of jacks, without in any way departing from the spirit and scope of my invention, as defined in the appended claims.

In disclosing my invention, the numeral 5 indicates the hollow jack cylinder and 6 its supporting base which is preferably made integrally therewith. Having a working fit in the bore of the cylinder 5 is a hollow ram 7, provided with a ram head 8 inclosing an enlarged cavity 9 which opens into the smaller diametered bore 10 of the ram piston. When the parts are in lowered position the ram head may rest upon the upper face of the cylinder as shown.

The numeral 11 represents the ram base which is exteriorly threaded to screw into the interiorly threaded base portion of the ram at 12, and integrally formed with the ram base 11 is an upwardly extending pump cylinder 13 located centrally of the piston bore. Forming the ram base and pump cylinder in one piece in this manner, overcomes leakage induced by packing working loose at joints between like members as ordinarily assembled.

Centrally located within the hollow ram 7 is the pump rod or plunger 14 which is adapted to receive a reciprocating movement through the usual rocker arm 15, rocker shaft 16, and operating handle 17, which latter is provided with a projecting stop portion 18 co-acting with a stationary

stop 19 on the ram head, with a view to limit downward movement of said handle.

The lower end of the pump rod 14 within the pump cylinder 13 has an enlarged plunger head formed by the packing 20, and is further provided with a valve chamber 21 leading upwardly through a restricted valve passage 22, controlled by the check or suction valve 23, to the branch ports 24 which 10 open preferably at a point above the plunger head and into the pump cylinder chamber 25. The valve head seats upwardly in the valve chamber 21; a screw plug 26 having channels 27 being screwed into the 15 lower end of the plunger.

Within the pump well 25^a and grooved in the lower portion of the walls of the pump cylinder 13 is an annular recess 28, and extending upwardly therefrom are communicating grooves 29 vertically cut in the cylinder walls at intervals as shown, the purpose of which is more fully described hereinafter.

As previously stated, the ram base 11 is 25 screwed at 12 into the ram, and to form a tight joint therebetween I provide a cup packing 30 secured in a circumferential recess in the base by a washer 31 and threaded nut 32. From the description thus far 30 stated, the simple construction and effective arrangement of the various parts of the jack will be readily apparent, and the comparatively total absence of packing is an advantageous feature in a jack of this class.

35 For the purpose of providing communication between the chamber beneath the ram base and the pump cylinder chamber, I provide a valve chamber 33 in the base leading to a restricted vertical passage 34 which 40 are controlled by a valve 35 normally held upwardly against its seat by a spring taking against a channeled valve bonnet 36 threaded in the chambered base.

As previously stated, the main object of 45 my invention, and that which I desire to claim, is the provision of a screening means in a structure of the class described, located and arranged substantially in the manner described with a view to effectually preventing intrusion of foreign matter in openings, or the like, which tends to detract from the effective operation of the jack.

To this end therefore, the several openings and passages referred to herein are protected by a lower perforate disk or screen A and an upper perforate cylindrical screen B.

To provide a large screening surface and also with a view to permit ready removal 60 for cleaning purposes, I preferably solder, or otherwise secure, the edges of the perforate disk A to the removable nut 32. For similar reasons the cylindrical screen B in like manner is circumferentially arranged 65 about a cylindrical member C removably se-

cured on the pump rod, and which has a portion of its length fitting about the pump cylinder 13. The member C has its upper end inclosed, and its walls slotted in any suitable manner, the slots 37 being entirely inclosed by the exteriorly arranged screen B, in the preferred manner as shown.

The operation of the jack will be clearly understood by a reference to the drawings. Concisely stated, it is as follows: The reservoir comprising the hollow head and hollow ram piston being filled with any suitable liquid in the customary manner, upon the up stroke of the pump rod the liquid passes through the screen B and flows through the passages 24, 22 and 21 into the pump well 25^a, the suction valve being unseated.

On the down stroke the suction valve seats and closes, and the liquid under pressure forces the valve open and passes through the communicating passage in the ram base into the lower portion of the cylinder, thus raising the ram piston toward the load by the excess pressure induced.

In lowering the jack, the operating handle is reversed in its socket so that the lug projects upwardly, permitting the handle to be depressed to lowest position when the screw plug on the plunger trips and unseats the discharge valve, permitting the liquid to pass up the passages 33 and 34 in the ram base into the pump well 25^a, where free circulation up past the plunger head is established by means of the annular recess 28 and grooves 29 to the cylinder chamber above, and then through the screen to clear its perforations of any intercepted foreign matter. Any dirt which may have accumulated in the chamber below the ram base and taken up by the fluid prior to the lowering of the jack is held by the screen A, instead of lodging in the discharge valve passages and valve seats. In a manner similar to that of screen B, the reverse flow of the fluid also acts to cleanse the screen A, as will readily be understood.

Other advantages of my invention will be apparent to those skilled in the art, and it will be understood that many variations 115 may be made in the form and arrangement of the screening mechanism, such as for example the screening device B instead of being secured on the plunger 14 may be secured to the pump cylinder, and such variation is considered within the spirit and scope of my invention as pointed out in the appended claims.

Having thus described my invention and illustrated its use what I claim as new and 125 desire to secure by Letters Patent is the following:

1. In a hydraulic jack, the combination of a standard, a hollow ram having a base portion provided with a passage there- 130

- through, a cylindrical member positioned centrally of the ram bore and whose walls form a pump well into which the passage opens, a plunger working in the pump well
- 5 5 provided with a passage at its lower end, and a screening device carried by the plunger and having a bearing on the said pump well and arranged with reference thereto that on actuation of the plunger the liquid
- 10 10 in the jack body passes through the screen before entering either of the passages.
2. In a hydraulic jack, the combination with a jack cylinder, of a ram movable in said cylinder and provided with a pump
- 15 15 cylinder, a plunger positioned to have its lower end work in said cylinder and formed with a passage in said lower end, and a screening device in operative relation with said plunger and pump cylinder and disposed with reference thereto and to said passage to screen the passage, substantially as described.
3. In a hydraulic jack, the combination with a jack cylinder, of a ram therefor
- 25 25 formed with a passage in its base and having a pump cylinder surrounding the upper terminal of said passage, a plunger positioned to work in said pump cylinder and adapted to force a flow of liquid through
- 30 30 said passage, and a screening device in operative relation with said plunger and pump cylinder and disposed with reference thereto and to said passage to screen the passage, substantially as described.
- 35 4. In a hydraulic jack, the combination
- with a jack cylinder, of a ram movable in said cylinder and having a base portion, actuating means for raising said ram comprising a plunger, said base portion and plunger being formed with communicating 40 passages through which liquid is adapted to flow, and a screening device positioned in said ram in operative relation with said plunger and base portion and disposed with reference thereto and to the said passages 45 to screen the passages, substantially as described.
5. In a hydraulic jack, the combination with a jack cylinder, of a movable ram therefor having a base portion, a liquid 50 pressure chamber underlying the base portion, the latter being formed with a passage through which liquid is adapted to flow from the chamber to the upper face of the base portion on depression of the ram, 55 and a screening device located in said chamber comprising a ring and a perforate screen peripherally carried by said ring, the ring engaging the base in such a manner that the screen surrounds the passage inlet 60 to positively screen the passage during the downward movement of the ram.

In testimony whereof, I have hereunto signed my name in the presence of the two subscribed witnesses.

EDWARD R. PENROSE.
